(57) **CLAIM**

(21) Appl. No.: **29/332,828**

The ornamental design for a meter set for motorcycles, as shown and described.

(22) Filed: **Feb. 26, 2009**

DESCRIPTION

(51) **LOC (9) Cl.** **12-16**

FIG. 1 is a front view of a meter set for motorcycles showing my new design;

(52) **U.S. Cl.** **D12/192**

FIG. 2 is a rear elevational view thereof;

(58) **Field of Classification Search** D12/192,

FIG. 3 is a left side elevational view thereof;

D12/110, 114, 126; 296/70, 190, 191; 180/90,

FIG. 4 is a right side elevational view thereof;

180/219, 220; 280/750-752, 288.1-288.4;

FIG. 5 is a top plan view thereof; and,

D10/46, 102, 98, 122-127; 73/495, 493;

FIG. 6 is a bottom view thereof.

116/62.4

See application file for complete search history.

The broken lines immediately adjacent the shaded areas represent the bounds of the claimed design while all other broken lines are directed to environmental structure; the broken lines form no part of the claimed design.
